(57) **CLAIM**

The ornamental design for a travel case, as shown and described.

DESCRIPTION

FIG. 1 is a front isometric view of our new design for a travel case.

FIG. 2 is a front elevation view of FIG. 1.

FIG. 3 is a back elevation view of FIG. 1.

FIG. 4 is a right elevation view of FIG. 1.

FIG. 5 is a left elevation view of FIG. 1.

FIG. 6 is a top plan view of FIG. 1.

FIG. 7 is a bottom plan view of FIG. 1.

FIG. 8 is a top plan view of the bottom half of the case of FIG. 1; and,

FIG. 9 is an exploded view of the case of FIG. 1.

The features shown in even-dash broken lines in the drawing depict portions of the article which form no part of the claimed design. The dot-dash broken lines represent boundaries of the claim and form no part of the claimed design.

1 Claim, 7 Drawing Sheets
